ROCKING CHAIR

Charles C. Witzel, Brooklyn, N. Y.

Application February 8, 1933, Serial No. 655,706

10 Claims. (Cl. 155—69)

This invention relates to rocking chairs and more particularly to that class known as convertible rocking chairs, the principal object of the invention being the provision of an improved 5 convertible rocking chair in which the rockers, while located to engage the floor, do not project beyond the front and rear of the body or seat of the chair, thereby doing away with the annoying and, at times, dangerous projections common 10 found in rocking chairs.

A further object of the invention is the provision of an improved convertible chair which may be used as a rocking chair, a reclining chair or as an ordinary chair at the option of the 15 user and which, notwithstanding the shortened form of the rockers, cannot readily tip over.

A still further object of the invention is the provision of an improved convertible chair, simple in construction, efficient in use, inexpensive 20 to manufacture and which, without the adjustment of any parts, can be readily converted by a slight motion of the body from an ordinary chair into a reclining chair or into a rocking chair and in which the rockers do not project 25 beyond the front and rear legs of the chair.

Rocking chairs, as ordinarily constructed with the rockers engaging the floor, have these rockers projecting forwardly and rearwardly of the seat and these projecting portions are not merely 30 annoying but dangerous to anyone moving about. Not only this, but they frequently mar and injure other articles of furniture, take up considerably more room than other chairs and are a nuisance generally.

Therefore, the present improvement provides a 35 rocking chair which will eliminate these disadvantages, take up no more room than an ordinary chair, have no projecting portions that will injure or mar other furniture or injure or annoy any- 40 one coming into contact therewith by day or night.

In the drawing accompanying and forming a 45 part of this specification, Fig. 1 is a side view of one form of this chair embodying the present improvement, the full lines illustrating the chair when used as an ordinary chair and the dotted lines illustrating the same when used as a reclining chair, and.

Fig. 2 is a similar view but illustrates the chair when used as a rocker.

Similar characters of reference indicate corresponding parts in the several views.

Before explaining in detail the present improvement and mode of operation thereof, I desire to have it understood that the invention is 55 not limited to the details of construction and ar-

angement of parts illustrated in the accompanying drawing since the invention is capable of other embodiments, and that the phraseology which I employ is for the purpose of description and not of limitation.

This improvement may be applied to various forms of chairs and also to such other articles as may be provided with rockers.

In the present instance, it is applied to an upholstered chair having a seat 2, a back 3 and 60 arms 4 forming what may be considered the body of the chair. The base of the seat is provided with a pair of depending front legs 5 and a pair of depending rearwardly inclined legs 6.

Intersecting a front and rear leg at each side 70 of the chair is a runner or rocker 7 and, as shown, this rocker terminates preferably inside the rear leg and extends under the front leg, being formed with a comparatively short rear curved portion 8 merging into a relatively long straight 75 portion 9 terminating in a slightly inclined portion at the front end 10.

The weight of the body of the user usually comes fairly close to or at the back of the chair and consequently is approximately in line with that 80 part of the rocker adjacent to where the curved and straight portions thereof meet. The result of this is that when the occupant sits normally in the chair, the straight portion of the rocker will engage the floor and the chair can be used as a 85 stationary or ordinary chair. When, however, the occupant leans slightly back, the curved portion of the rocker is brought into engagement with the floor, whereupon the chair can be used as a rocker and when he leans farther back, the chair 90 can be tilted to the rear and used as a reclining chair, in which position, the lower ends 11 of the rear legs which project slightly below the rockers, will engage the floor and stop the tilting of the 95 chair any farther and also prevent tipping over.

Experiment has demonstrated that only a comparatively small portion of the ordinary rocker of a chair engages the floor so that a considerable portion of the rocker does not perform any work and is a waste of material and, by actual test, it 100 has been found that the comparatively small rocking portions of this chair are amply sufficient to provide a full rocking action of the chair so that this improved chair can be readily converted from the ordinary chair into a rocking chair or 105 into a reclining chair at the will of the user by a slight motion of the body and without the addition of any mechanism or the adjustment of any part of the chair.

Thus, I have provided an improved chair which 110

is readily convertible from an ordinary chair to a rocking chair or into a reclining chair and in which the rockers do not project beyond the front and back of the seat, whereby less material is required and the cost of manufacture is materially lessened without in any way interfering with the efficiency of the chair.

One of the advantages of this improved chair is that it can be moved around on its rockers or 10 runners over a rug or the edges of a rug by a woman very easily without the necessity of lifting the chair as is the case with the ordinary four-leg heavy upholstered chair. Another of its advantages is that it has all of the comforts of the 15 old style Morris chair when it is tilted without its unsightly appearance and the necessity of adjusting the back and is much more easily handled.

It is to be understood that, by describing in detail herein any particular form, structure or 20 arrangement, it is not intended to limit the invention beyond the terms of the several claims or the requirements of the prior art.

Having thus explained the nature of my said invention and described a way of constructing 25 and using the same, although without attempting to set forth all of the forms in which it may be made or all of the modes of its use, I claim:

1. An article of manufacture comprising a seat provided with legs connected by rockers, each 30 rocker terminating at the legs so as not to project therebeyond and not substantially beyond the seat base, said rockers having an integral floor engaging part between the legs constructed to hold the article in an upright position, another 35 part integral therewith between the legs constructed to rock the article and another integral part constructed to co-operate with the rear legs to hold the article in a reclining or tilting position.

2. An article of manufacture comprising a seat 40 provided with legs connected by rockers, each rocker terminating at the legs so as not to project therebeyond and not substantially beyond the seat base, said rockers having an integral floor engaging part between the legs constructed to hold the article in an upright position, another 45 part integral therewith between the legs constructed to rock the article and another integral part constructed to co-operate with the rear legs to hold the article in a reclining or tilting position, the rocking parts being located between the 50 other parts and toward the rear of the rockers.

3. A convertible chair comprising a seat and front and rear legs provided with rigid rocking members supporting said legs and terminating 55 thereat, thereby eliminating obstructions beyond the front and rear of said legs and substantially beyond the seat base, each rocking member comprising a one piece member having a straight portion to hold the chair in its normal position and terminating in a curved portion for rocking movement of the chair and terminating in a portion co-operating with a rear leg to hold the chair in a tilted position, all of said portions being within the limits of the front and rear legs.

4. A convertible chair comprising a seat having 65 depending front and rear legs, a pair of rockers connecting the lower ends of said legs and terminating thereat and not projecting substantially beyond the seat base and extending under the front legs, each of said rockers having a comparatively short rear curved portion terminating a relatively long straight portion, the curved portion extending upwardly and joining the rear leg above the terminus thereof.

5. A convertible chair comprising a seat having depending front and rear legs, a pair of rockers connecting the lower ends of said legs and terminating thereat and not projecting substantially beyond the seat base and extending under the front legs, each of said rockers having a comparatively short rear curved portion terminating a relatively long straight portion, the curved portion extending upwardly and joining the rear leg above the terminus thereof, the rear legs projecting 80 below the rockers and forming stops. 85

6. A convertible chair comprising a seat having depending front legs and rearwardly inclined rear legs, a pair of rockers connecting the ends of said legs and terminating thereat and not projecting substantially beyond the seat base and extending under the front legs, the rear legs projecting below the rockers and forming stops, each of said rockers having a comparatively short rear curved portion terminating a comparatively long 90 straight portion in front thereof. 95

7. An article of manufacture comprising a seat provided with rockers in position to engage the floor and terminating within the limits of the front and rear legs whereby the rockers do not 100 project therebeyond and not substantially beyond the seat base, each of the rockers having its rocking portion adjacent to the rear end thereof and closer to the rear legs than to the front legs and terminating in a stop to permit the article to be tilted into a reclining position, said stop being spaced below the rear terminus of the rocker. 105

8. A chair having front and rear legs, rocker elements extending between the front and rear 110 legs and terminating within the confines of said front and rear legs, each of said rocker elements having an elongated straight front portion and a relatively short upwardly curved rear portion, and the rear leg being extended and projecting 115 below the rear end of said rocker element to form a stop and to stabilize said chair in rearward position.

9. A chair having front and rear legs, rocker elements extending between the front and rear 120 legs and terminating within the confines of said front and rear legs whereby the rockers do not project therebeyond, each of said rocker elements having an elongated straight front portion and an upwardly curved rear portion, said chair having a part projecting below each of said rocker elements adjacent to its rear end to form a stop and to stabilize said chair in rearward position, whereby the chair may be used as a straight chair, a rocking chair or a reclining chair. 125 130

10. An article of manufacture comprising a body having a seat, depending front and rear supporting members or legs, rocker elements carried thereby and having no relatively movable parts, each of said rocker elements having an elongated straight portion and a shorter curved portion of less than half the length of said straight portion and not extending substantially beyond the depending members or body whereby the body will always remain in a normally straight or upright position even when the user normally leans back, and a rigid stop projecting below the terminus of the curved portion adjacent to one of the depending supporting members or legs to stabilize the body in a tilted 135 or reclining position, whereby the article may be used in a straight position, rocking position or in a tilted or reclining position. 145

CHARLES C. WITZEL.
